LUFFING CRANE

Guy Taite Shoosmith, Chislehurst, England, assignor to Clarke, Chapman & Company Limited, Gateshead-on-Tyne, England, and said Shoosmith.

Application September 28, 1943, Serial No. 504,174
In Great Britain January 20, 1943

8. Claims. (Cl. 212—8)

This invention has reference to improvements in cranes, the main object being to enable the load to be transferred by the luffing of the jib, without slewing the crane, through a greater distance than is usual.

In known constructions of luffing cranes the distance that the load can be transferred by luffing the jib is limited to something less than the effective length of the jib since the jib in luffing moves in a plane which cuts the crane mast or post so that the jib cannot pass the crane mast or post and the load cannot be transferred from one side to the other of the crane simply by luffing the jib.

In a crane according to the present invention the jib and its pivot are so constructed and arranged that the jib can be luffed or turned about its pivot through an arc extending on each side of the vertical plane containing the axis of the pivot and the head of the jib during the luffing movements, instead of travelling in a vertical plane which cuts the mast or post, travels in a plane which is clear of the crane mast or post so that the jib is not prevented from being luffed from one side of the crane to the other.

In order that the jib head sheave may properly support the hoisting rope throughout the extended luffing movement of the jib from one extreme inclined position to the other reversely inclined position, the axles of the jib head sheave or sheaves and the mast or post head sheave or sheaves are carried by swivelling forks and the jib head sheave axle is maintained substantially horizontal whatever the position of the jib.

In the accompanying illustrative drawings, Figs. 1 and 2 are elevations at right angles of a luffing and slewing crane according to the invention, the jib being shown in Fig. 1 luffed out and in Fig. 2 vertical in the plane of its pivot.

Fig. 3 is a plan view.

Fig. 4 is a diagrammatic view illustrating the arrangement of the ropes for obtaining level luffing of the load.

The crane structure *a* may be arranged on a base *b* either fixed or travelling of usual design. The base is shown provided with a bearing *c* for the foot of the structure *a*, a circular path or rail *d* for guide rollers *e* on the structure and a rack *f* engaged by a pinion *g* driven through gearing from a motor on the structure *a*.

The structure *a* is formed with a mast or post portion *a'* which is offset as regards the slewing axis of the structure and with an operator's cabin *a²*. In the head of the portion *a'* is a bearing in which is mounted the tubular shank of a swivelling fork *i* that carries caster fashion sheaves *j* and *j'*

the axis of the bearing being tangential to the sheaves.

The jib *k* is mounted on a pivot *k'* located on the structure laterally of the mast or post portion *a'* and radial to the axis of the shank of the fork *i*; the major axis of the jib lies at an angle to the pivot *l* and when the jib is luffed vertical in the plane of its pivot (Fig. 2) the jib is clear of the portion *a'*. In the head of the jib *k* is a bearing which receives the shank of a swivelling fork *l* that carries a sheave *m* for the hoisting rope *n*. The shank of the fork *l* is set at an angle in the jib head such that if its axis were extended it would cut the extended axis of the shank of the fork *i* on the mast or post *a'* at a point in line with the axis of the jib pivot *k'*. The forks *i* and *l* are connected by pairs of rods *o* and *o'* which are articulated at the one end to the respective forks; at the other end the rods *o* and *o'* are respectively provided with cross members *p* and *p'* formed with holes the rods *o* passing through the members *p'* and the rods *o'* passing through the members *p*. This arrangement of swivelling sheave forks and rods permits the distance between the forks *i* and *l* to vary during luffing of the jib whilst maintaining the axle of the jib head sheave *m* virtually horizontal and the axles of the sheaves *j* and *j'* parallel so that the hoist rope *n* is properly supported on the sheaves throughout the luffing movements of the jib.

Other means for instance spur gear, may be used to cause swivelling of the jib head fork corresponding to the movement of the jib.

The jib beyond its pivot is shown provided with a balance weight *r* and with a circular rack *s* which is engaged by a spur gear *t* motor driven to effect luffing of the jib. Luffing may be effected by other means for instance by a crank drive or by hydraulic ram or by means of ropes.

The hoist or load rope *e* passes from the sheave *j* down through the shank of the fork *i* round a sheave *u* (which may be fixed or as shown attached to weighing gear *v*) on the structure *a*, thence over a sheave *w* which is mounted to slide in guides *x*, to the hoisting drum *y*; the sheave *w* is mounted in a bridle *z* attached to a rope *l* which passes round fixed sheaves *2* and *3*, up through the shank of the fork *i*, over a sheave *j'* on the same axis as the sheave *j* and is secured to the member *p'* of the rods *o'*. With suitable relative arrangement of the jib *k* and the mast or post *a'* level luffing is thus provided for as any luffing of the jib alters the position of the sheave *w* and so compensates for variation in the vertical position 55 of the load that would follow the raising and low-

ering of the sheave m . Other means of securing level luffing of the load may be used.

A suitable distance between the pivot l and the sheaves j j' is about one third of the distance between the pivot k^x and the sheaves m .

As will be seen from Fig. 1 the load can be transferred by luffing the jib without slewling the crane structure from the position shown in full lines on one side of the crane to the position shown in dotted lines on the other side of the crane, thus enabling the working speed to be increased.

The jib head travels in a plane tangential to the mast or post as indicated in Fig. 2.

As cranes according to the invention do not need to be slewed to transfer loads through considerable distances, they can work close alongside each other.

As will be understood, instead of a single load rope, a number of ropes or a set of grab-operating ropes can be used, the required number of sheaves being provided.

What I claim is:

1. A luffing crane comprising a crane structure, a pivot on said structure, a jib on said pivot, a post on said structure extending above said pivot, a sheave on said post, a second sheave on said jib, a hoisting rope passing over said sheaves, the jib and its pivot being so arranged that the jib can be luffed or turned about its pivot through an arc extending on each side of the vertical plane containing the axis of the pivot, the head of the jib during the luffing movements, instead of travelling in a vertical plane which cuts the mast or post, travelling in a plane which is clear of the crane mast or post.

2. A luffing crane according to claim 1 in which the post and jib sheaves are carried by swivelling forks and the axle of the jib sheave is maintained substantially horizontal whatever the position of the jib.

3. A luffing crane according to claim 1 in which the jib pivot is located radially and laterally of the post and the jib lies at an angle to the pivot and when luffed vertical in the plane of its pivot is clear of the mast or post.

4. A luffing crane comprising a crane structure with mast or post and a jib pivoted to the structure, the jib and its pivot being so arranged that the jib can be luffed or turned about its pivot through an arc extending on each side of the vertical plane containing the axis of the pivot, the head of the jib during the luffing movements, instead of travelling in a vertical plane which cuts the mast or post, travelling in a plane which is

clear of the crane mast or post, the jib pivot being located radially and laterally of the post and the jib lying at an angle to the pivot and when luffed vertical in the plane of its pivot clearing the post, a hoisting rope passing over post and jib sheaves which are carried by swivelling forks and the axle of the jib sheave being maintained substantially horizontal whatever the position of the jib.

5. A luffing crane according to claim 1, in which the post and jib sheaves are carried by swivelling forks and the axle of the jib sheave is maintained substantially horizontal whatever the position of the jib, and in which the swivelling forks at the post and jib have articulated to them pairs of rods telescopically arranged but adapted to prevent relative rotary movement.

6. A luffing crane comprising a crane structure with mast or post and a jib pivoted to the structure, the jib and its pivot being so arranged that the jib can be luffed or turned about its pivot through an arc extending on each side of the vertical plane containing the axis of the pivot, the head of the jib during the luffing movement, instead of travelling in a vertical plane which cuts the mast or post, travelling in a plane which is clear of the crane mast or post, a hoisting rope passing over post and jib sheaves which are carried by swivelling forks and the axle of the jib head sheave being maintained substantially horizontal whatever the position of the jib, the swivelling fork of the jib sheave having its shank set at an angle such that if its axis were extended it would cut the extended axis of the shank of the post swivelling fork at a point in line with the axis of the jib pivot.

7. A luffing crane according to claim 1, in which the post and jib sheaves are carried by swivelling forks and the axle of the jib sheave is maintained substantially horizontal whatever the position of the jib, and in which the swivelling forks at the post and jib have articulated to them pairs of rods telescopically arranged but adapted to prevent relative rotary movement, the pair of rods articulated to the jib swivelling fork being connected to a rope which passes over sheaves and supports a sliding sheave over which the hoist rope passes whereby level luffing is provided for.

8. A luffing crane according to claim 1 in which the hoisting rope passes over a slidale sheave which is connected with the jib so that its position varies according to the position of the jib, whereby level luffing is provided for.

GUY TAITE SHOOSMITH.
